UNITED STATES PATENT OFFICE.

AUGUSTA Y. JANSEN, OF CHICAGO, ILLINOIS.

FLASH-LIGHT ELECTRICAL ALARM AND BANK AND CALL CLOCK.

No. 882,320.

Specification of Letters Patent. Patented March 17, 1908.

Application filed March 9, 1907. Serial No. 361,563.

To all whom it may concern:

Be it known that I, AUGUSTA Y. JANSEN, a citizen of the United States, residing at Chicago, in the county of Cook and State of Illinois, have invented certain new and useful Improvements in Flash-Light Electrical Alarm and Bank and Call Clocks; and I do hereby declare the following to be a full, clear, and exact description of the invention, such as will enable others skilled in the art to which it appertains to make and use the same.

This invention relates to improvements in flash light electrical alarm and bank clocks. 15 The invention comprises the provision of a clock, a plurality of alarms set in motion by the alarm mechanism of the clock, a light for illuminating the face of the clock, and a coin receptacle or bank formed in the shape of a bell.

20 The invention further comprises the provision of a battery connected to said clock and bell for operating the bell at any predetermined time and also connected to a lamp 25 for illuminating the face of the clock as may be desired.

With these and other objects in view the invention comprises certain novel combination, constructions and arrangements of parts, as will be hereinafter more fully described and claimed.

In the drawings:—Figure 1 is a front elevation of my invention. Fig. 2 is a rear elevation of the device shown in Fig. 1. Fig. 3 is a dotted top plan view of my invention, the electric circuits being shown in full lines to better disclose the same.

40 In connection with a clock mechanism proper it has been found desirable to have a number of auxiliary attachments for various purposes secured thereto, in connection therewith for accomplishing various results.

In the present invention I have provided a bank in connection with a clock mechanism, 45 the bank being an imitation of a bell. An alarm bell also is positioned adjacent to the clock mechanism proper together with an electric light for illuminating the face of the clock. These combinations and arrangements of parts provide a device that is very desirable and useful.

Referring more particularly to the drawing, 1 indicates a metallic frame work or base, and 2 and 3 are uprights secured to the 55 base 1 by any suitable means as bolts 4, 5 and 6. The bolt 6 is adapted to engage at one

end a lug 7 formed on the base 1 and at the other a lug 8 formed on the upright 3. This bolt is adapted to firmly hold a clock 9 in position on the base 1 between the uprights 2 and 3, by acting on lug 8 and drawing the two uprights toward each other.

In order to more firmly hold the clock 9 in position upon the base 1 a securing means, as 10, passes through one point of the outer casing of the clock as clearly seen in Fig. 2 of the drawing. The securing means 10 also provides a good electric contact between the clock and the base. Secured to the front of the upright 2 is an electrically operated bell 11 of any desired or usual construction, while to the upright 3 is secured a bank 12 formed in substantially the same shape as the bell 11 so as to give the appearance of a double electric bell. A suitable slot 13 is formed in the top of the bank in the usual manner of such devices for accommodating various size coins. The back of the bank 14 is firmly secured in position by any desired securing means as screws 15 while to the back 14 and the bell-shaped front is hinged at 16 and is locked to the back by locking means 17.

An electric lamp of any desired construction, as 18, is positioned in front of the clock for illuminating the same whenever it may be desired. Suitable batteries, as 19 and 20, are secured in position back of the uprights 2 and 3 for providing the necessary electric current for the lamp 18, and also for operating the bell 11. A suitable push button, as 21, is provided for closing the circuit of the lamp 18 and may be positioned at any desired place so that the same may be operated to illuminate the face of the clock, even when the operator is in bed. The push button is made in the usual manner with the exception that the button 22 is made of metal so as to provide a secondary circuit for the batteries 19 and 20 for operating the bell 11.

Referring more particularly to Fig. 3 of the drawings the circuit of the bell and battery may be more easily traced. Starting with the binding post 23 current will flow through wire 24, battery 19, which augments the current passing therethrough, wire 25, binding post 26, wire 27, push button 21, wire 28, wire 29, lamp 18, wire 30, wire 31, to binding post 32 of battery 20. When the button 21 is pushed current will flow in the circuit just traced and cause the lamp 18 to illuminate the face of the clock, as will be evident.

In case it is desired to use my invention as a call bell, it will be only necessary to press the metallic button 22 against the base 1 or in fact any part of the metal frame-work of my invention until the button has closed the circuits of wires 27 and 28, and the current from batteries 19 and 20 will ring the bell 11, as well as light the lamp 18. Tracing the circuit of the bell 11 when used as a call bell, 5 when pressing the metallic button 22 against the frame-work 1, the current will flow from binding post 23, through wire 24, battery 19, and receive additional current from the battery 19, wire 25, binding post 26, wire 27, 10 metallic button 22, frame 1, wire 33, through the windings of bell 11, wire 31, back to binding post 32 of battery 20. At the same time that the circuit through the bell is formed, it will be perfectly evident that the 15 lamp circuit will also be formed. By this construction when it is desired only to light the lamp 18, it is only necessary to press the button 21, but when it is desired to ring the bell it is necessary to press the metallic button 20 against the base 1.

When it is desired to use the bell 21 as an alarm in connection with the clock 9, the alarm mechanism of the clock is provided with a rotating arm 34 which is positioned 20 out of contact with arm 35. The arm 35 is connected with binding post 23 so that when the alarm mechanism of the clock rotates arm 34, until the arm contacts therewith, a circuit will be formed in which current will 25 flow from the binding post 23 through arm 35, arm 34, clock 9, and base 1, wire 33, through the winding of bell 11, wire 31, and back to wire 20 and the binding post 32.

When the alarm mechanism of the clock 30 rotates arm 34 until it contacts with arm 35, the bell will continue to ring until the battery 20 is exhausted, unless arm 34 is moved out of contact with arm 35. When the bell 35 is operated by the circuit just described, in order to conveniently break the circuit, the arm 34 is slightly rotated and an insulating sleeve 36 is interposed for holding the circuit open. When the circuit is open, the

bell 11 cannot be operated again by the alarm mechanism of the clock 9 until the 50 sleeve 36 has been removed and arm 34 having been rotated away from arm 35, and set to be again brought in contact with arm 35, at any desired time by the alarm mechanism of the clock.

What I claim as new and desire to secure by Letters Patent is:—

1. A device of the character described comprising a clock provided with an alarm arbor, an electrical bell, a circuit for said bell, 60 means connected with said arbor to interrupt said circuit, means for supplying current to said bell, an electrical lamp, a circuit for said lamp, a circuit parallel with said first mentioned circuit, and a metallic push 65 button switch for closing the circuit of said lamp when pressed and completing the circuit of said bell when pressed against said clock.

2. A device of the character described 70 comprising a clock, an electrically operated bell in electrical connection with said clock and adapted to be set into operation thereby, an electrical lamp, means operated by said clock for closing the circuit of said bell and a 75 metallic push button interposed in the circuit of said lamp and said bell whereby when said button is pressed against the clock said bell will operate and said lamp will be lighted.

3. A device of the character described 80 comprising a clock, an electrically operated bell designed to be set into operation by said clock, an electrical lamp, an electrical circuit for said bell, an electrical lamp, a source of current for both of said circuits, and a metallic push button for closing 85 said lamp circuit when pressed and for closing both circuits when pressed against said clock.

In testimony whereof I affix my signature 90 in presence of two witnesses.

AUGUSTA Y. JANSEN.
